ASH TRAY

Earle M. Brunsvold, Glen Lake, Minn.

Application March 1, 1950, Serial No. 147,029

1 Claim. (Cl. 220—20.5)

1

This invention relates generally to ash trays and specifically to a pocket sized ash tray.

It is an object of my invention to provide a relatively small compact unit constructed to provide a pocket size ash tray.

It is another object to provide an ash tray of the rotary receptacle type and provided with a positive ejector mechanism for removing the cigarettes from the rotor.

It is still a further object to provide an ash tray having a relatively small snuffing compartment in which the cigarettes are extinguished by the lack of air supply and having a dumping mechanism for discharging the extinguished cigarettes into a storage compartment.

These and other objects and advantages of my invention will more fully appear from the following description made in connection with the accompanying drawings wherein like reference characters refer to the same or similar parts throughout the several views and in which:

Fig. 1 is an end elevational view of my pocket ash tray;

Fig. 2 is a front elevational view of said ash tray;

Fig. 3 is a top plan view thereof;

Fig. 4 is a vertical transverse sectional view taken substantially along the line 4—4 of Fig. 2; and

Fig. 5 is a fragmentary sectional view taken substantially along the line 5—5 of Fig. 4.

As best shown in the accompanying drawings I provide an extremely compact relatively simple pocket size ash tray having a casing formed in two sections respectively designated by the numerals 7 and 8 designating the upper and lower sections. The lower section 8 forms an ash receiving compartment and has a closure across the top thereof in the form of a pivotally mounted trap door member 9. The member 9 is trunnioned in the end portions 8a adjacent the upper sides thereof and substantially adjacent the front panel of said lower section 8. An operating handle or lever 10 is fixed to the outside of one of the trunnions, as best shown in Fig. 1. A substantially cylindrical chamber is formed in the upper section 7 of the casing and has an opening 11 at the top thereof and an opening 12 across the bottom thereof. A rotary member 13 is journaled for rotation within said cylindrical chamber and has a pair of diametrically opposed cigarette receiving recesses 14 and 15 formed across opposite sides thereof. A knurled knob 16 is fixed to at least one end of said rotary member 13 to permit the same to be easily rotated. These

2

recesses 14 and 15 are adapted to be selectively aligned with the openings 11 and 12 in the cylindrical chamber of the upper casing section and each has an ejection member extending thereacross. The ejection member in recess 14 is designated by the numeral 17 and in recess 15 by the numeral 18. A pair of apertures are formed through the narrow central portion of the rotary member 13 to afford communication between the recesses 14 and 15 and a pair of rods 19 securely interconnect said ejector elements 17 and 18 and extend through said apertures as best shown in Figs. 4 and 5.

The upper casing section 7 and the lower casing section 8 are removably interconnected as best shown in Figs. 4 and 5 and a pair of trunnion receiving opposed notches are formed in the respective end portions of the lower marginal portion of section 7 to permit the same to receive the trunnions of said trap door 9. The bottom of each of the recesses 14 and 15 is semi-cylindrical in shape and the inner peripheral surfaces of the ejector elements 17 and 18 are substantially semi-cylindrical in shape to conform to the inner extremities of the recesses as best shown in Fig. 4.

The following is a description of the operation of my improved ash tray. One of the recesses, either 14 or 15, is disposed upwardly underlying the opening 11. Fig. 4 shows a cigarette lying in the recess by the dotted line. Ashes may also be deposited into the recess and when the same becomes full or it is desired to dump the same the knurled knob 16 is turned by pressure of the thumb or one of the fingers thereagainst and as the rotary member 13 swings within its cylindrical chamber the relatively heavy ejector element will force the cigarette and ashes out of the recess and completely clean the same. If additional pressure is needed this may be produced on the upper ejector element to force the lower one down and positively eject any material therefrom. The cigarettes and ashes fall from the recess onto the trap door 9 in which a lack of air soon extinguishes any burning portions of the cigarette or ashes. When it is sure that these burning coals have been extinguished the trap door is dumped by downward pressure on the lever 10 to swing the door on its trunnions. This deposits the extinguished ashes and cigarettes into the ash receiving compartment in the lower portion of the bottom casing section 8.

It will be seen that I have provided an extremely compact and novel ash tray which can be easily carried in the pocket of the user or

in a woman's purse. It is proposed that this ash tray would be the approximate size of a pack of cigarettes. The mechanical combination of the ejector elements and the rotary member having the recesses therein seals off the lower ash receiving compartment and permits a substantially clean recess to be always available for use, while at the same time permitting a relatively large storage space below the rotary element. The trap door 9 combines with the rotary element and ejector elements to form a substantially sealed relatively small chamber in which there is insufficient air to support combustion for any substantial period. The trap door actuating member or handle 10 provides a relatively simple and efficient means for dumping the extinguished ashes and cigarette butts into the ash receiving chamber.

It will, of course, be understood that various changes may be made in the form, details, arrangement and proportions of the parts without departing from the scope of my invention.

What I claim is:

An ash tray comprising a hollow casing, an elongated rotary ash-receiving member horizontally journaled in the upper portion of said casing and having at least one pair of grooves longitudinally formed therein and extending at least substantially the full length thereof, the

grooves being diametrically opposed one to the other, a weighted shiftable element mounted in each of said grooves and extending substantially the full length thereof with freedom for shifting movement transversely of the rotary ash-receiving member, means for interconnecting the shiftable elements in the respective grooves whereby the weight of both elements will urge the upper element into retracted seated position and the lower element into outwardly projected ejecting position, and means for rotating said rotary member on its longitudinally horizontally disposed axis.
